LAND.

BOTTLE-CAPPING MACHINE.

1,030,164.

Specification of Letters Patent.

Patented June 18, 1912.

Application filed September 29, 1909, Serial No. 520,087. Renewed January 9, 1912. Serial No. 670,132.

To all whom it may concern:

Be it known that I, Ross V. CRAGGS, a citizen of the United States, and residing at Baltimore, in the State of Maryland, have 5 invented certain new and useful Improvements in Bottle-Capping Machines, of which the following is a specification.

This invention relates to a fluid pressure operated bottle capping machine and the object thereof is to provide a machine of such class in a manner as hereinafter set forth and claimed whereby the capping of bottles with what is termed a metallic cap and seal will be efficiently had with the liability 15 of breakage of the bottle neck reduced to a minimum.

A further object of the invention is to provide a machine of the class referred to in a manner as hereinafter set forth and 20 claimed which is adapted for use in connection with bottles of varying heights without the employment of vertical adjustable supports for the bottles to properly position them with respect to the capping elements of the machine and furthermore embodying means constituting automatically 25 adjustable independent cap crimping elements to conform to varying diameters of bottle necks.

30 A further object of the invention is to provide a machine of such class with means in a manner as hereinafter set forth and claimed, whereby the capping elements of the machine will be automatically returned 35 to inoperative position after the cap has been crimped upon the bottle neck.

A further object of the invention is to provide a machine of such class with means in a manner as hereinafter set forth where- 40 by the capping elements during their move- ment toward and from operative position will be cushioned to overcome any liability of breakage of the bottle neck due to a quick stroke when the elements are moved to cap- 45 ping position and to overcome any liability of injury to the capping elements due to quick return stroke.

A further object of the invention is to 50 provide a machine of the class referred to with means in a manner as hereinafter set forth and claimed to constitute a cap-retaining element whereby the cap will be securely held upon the bottle neck to prevent 55 any possibility of bulging during the crimping operation and to further constitute

means for operating the crimping element for the cap to fixedly secure the cap to the bottle neck subsequent to the operation of the retaining means.

Further objects of the invention are to 60 provide a fluid pressure operated bottle cap- 65 ping machine which shall be comparatively simple in its construction and arrangement, strong, durable, efficient in its use, readily set up, reducing the liability of breakage of bottle necks to a minimum, and compara- 70 tively inexpensive to manufacture.

With the foregoing and other objects in view, the invention consists of the novel construction, combination and arrangement 75 of parts as hereinafter more specifically described and illustrated in the accompanying drawings, wherein is shown the preferred embodiment of the invention, but it is to be understood that changes, variations and 80 modifications can be resorted to which come within the scope of the claims hereunto appended.

In the drawings wherein like reference characters denote corresponding parts 80 throughout the several views: Figure 1 is a vertical sectional view of a fluid pressure operated bottle capping machine in accordance with this invention. Fig. 2 is a side elevation. Fig. 3 is a vertical sectional 85 view of the upper portion of the machine taken at right angles to that shown in Fig. 1. Fig. 4 is a section on line X—X of Fig. 3 looking in the direction of the arrow. Fig. 5 is a sectional detail illustrating the 90 two-way valve, and Fig. 6 is a perspective view of the machine.

As shown in Fig. 6 the machine is supported upon an upright 1 carrying a block 2 which is fixedly secured to the machine and is also 95 provided with a bottle-centering member 2^a. The lower end of the upright 1 is connected to a base 3 carrying a guide 4 for position- 100 ing the bottle 5 in the path of the crimping element. The foregoing manner of support- 105 ing the machine is illustrated by way of example as it is obvious that any suitable means for supporting the machine as well as positioning the bottle can be employed.

The machine comprises a cylinder 6 hav- 105 ing an outwardly extending annular flange at its upper and at its lower end, said flanges being indicated by the reference characters 7 and 8. The flange 8 is formed with a screw-threaded nipple 9 which communi- 110

cates with the interior of the cylinder 6 by the port 10^a. Mounted against the flange 8 is a closure head 10 for the lower end of the cylinder 6 and which is recessed as at 11 to 5 provide a pocket 11. The head 10 has depending therefrom a packing box 12 which is flanged as at 13 and extending in the box 12 is a packing gland 14 flanged as at 15 which opposes the flange 13 and is adjustably se- 10 cured to the flange 13 by the bolts 16. Within the packing box 12 is arranged a packing 15 17. The head 10 is connected to the flange 8 through the medium of the hold- fast devices 18 and said head 10 is formed 19 on its upper face with a cylindrical off-set 19 which extends into the cylinder 6 and engages the inner face of said cylinder.

Mounted upon the flange 7 is a head 20 for closing the upper end of the cylinder 6 20 and the said head 20 has its lower face formed with a cylindrical off-set 21 which extends into the cylinder 6 and snugly engages the inner face of the said cylinder 6. The head 20 is connected to the flange 7 by 25 the hold-fast devices 22 and is provided with a pocket 23, with a port 24 which communicates with the interior of the cylinder and is arranged at one side of the pocket 23 and furthermore with a port 24^a 30 which communicates with the interior of the cylinder 6 and is arranged at one side of the pocket 23. The head 20 is also formed with a screw-threaded recess 25 having the inner portion of its wall beveled as at 26, 35 said recess 25 communicating with the port 24^a.

Mounted upon and secured to the head 20 is a plate 27 provided with an upright 28 carrying an integral valve casing 29 which 40 is closed at one end by a cap 30 and provided with an outlet port 31. Communicating with the valve casing 29 is a motive fluid supply pipe 32 and also communicating with the valve casing 29 is a motive fluid 45 conducting pipe 33, the latter leading to an L 34 which is connected to the nipple 9. The valve casing 29 is provided with a port 35 which opens into the conducting pipe 33 and is also provided with a nipple 36 which 50 opens into the motive fluid supply pipe 32. The upright 28 is formed with a passage 37 which opens at one end into the interior of the valve casing 29 and at its other end opens into the port 24.

55 Arranged within the valve casing 29 is a two-way valve 38, the passages therein being indicated by the reference characters 39 and 40. The valve 38 is formed with a stem 41 which projects from that end of the casing 29 which is not provided with the cap 30 and mounted upon the projecting end of the stem 41 is a holding lever 42 provided with a nose 43 and a handle 43^a. Interposed between the lever 42 and the casing 29 and 60 surrounding the stem 41 is an actuating

spring 44 for automatically shifting the valve in one direction when the lever is released in a manner to be hereinafter referred to. One end of the spring 44 is fixed to the valve stem 41 and at its other end to the upright 28 as at 45. The pipe 32 is provided with a regulating supply valve 46, whereby the pressure supplied can be regulated. 70

The passage 39 of the valve 38 is termed 75 the exhaust passage for the motive fluid and the passage 40 is termed the supply passage for the motive fluid and in this connection it will be stated that the passage 40 is adapted to alternately establish communication between the conducting pipe 33 and the supply pipe 32 and between the passage 37 and supply pipe 32 and the passage 39 is adapted to alternately establish communication between the conducting pipe 33 and 80 outlet 31 and between the passage 37 and outlet 31. The normal position of the valve 38 is such that the passage 40 will establish communication between the supply pipe 32 and the passage 37 and the passage 39 of 90 the valve 38 will establish communication between the conducting pipe 33 and the outlet 31.

Arranged within and projecting from the cylinder 6 is an inner and an outer piston, 95 the outer piston being indicated by the reference character 47 and the inner piston by the reference character 48. The piston 47 has operating therethrough the piston 48 and the piston 47 extends through an opening 49 formed in the head 10 and also extends through the packing box 12 and gland 14. The piston 48 snugly fits the piston 47 but the fit is such as not to interfere with the movement of the piston 48. The piston 100 47 at its upper end is cup-shaped as at 50 and is of such a diameter as to snugly engage the inner face of the cylinder 6, the cup-shaped portion being provided with peripheral packing rings 51 and further having an extension 52 adapted to engage in the pocket 11 on the downward movement of the piston 47. The inner face of the cup-shaped portion 50 of the piston 47 is shouldered as at 53 for a function to be herein- 110 after referred to. The upper edge of the cup-shaped portion 50 of the piston 47 constitutes a pressure impacting surface and which is indicated by the reference character 54. The upper portion of the piston 115 48 is formed of two different diameters, the larger being indicated by the reference character 55 and the smaller by the reference character 56, that portion of larger diameter is arranged within the cup-shaped portion 120 50 of the piston 47 and is adapted to engage the shoulder 53 so that on the downward movement of the piston 48, it will carry the piston 47 therewith. That portion of 125 smaller diameter 56 of the piston 48 extends 130

- into the pocket 23 formed in the head 21. The pocket 11 as well as the pocket 23 constitute what may be termed cushioning chambers, the pocket 11 forming a cushioning chamber for the extension 52 on the downward movement of the piston 47 and the pocket 23 forming a cushioning chamber for the upper end 56 of the piston 48 on the upward movement of the said piston 48.
- 5 The top edge of that portion 55 of larger diameter of the piston 48 constitutes a pressure impacting surface and which is indicated by the reference character 57. The shoulder 53 on the upward movement of the piston 57 is adapted to engage the lower face 58 of the portion 55 of the piston 48 so as to shift the said piston 48 upwardly on the upward movement of the piston 47. The portions 59 and 60 of the lower face of the cup-shaped upper end 50 of the piston 47 constitute pressure impacting surfaces whereby the piston 47 is shifted upwardly when motive fluid is supplied to the lower end of the cylinder 6. The disposition of the piston 47 with respect to the piston 48 is such that the piston 48 will move downwardly slightly in advance of the piston 47 and when the shoulder 53 is engaged by the piston 48, the two pistons move together.
- 10 The piston 48 is what may be termed a cap holding piston and the piston 47 is what may be termed a crimping die operating piston for the reason that the function of the piston 48 is to cause the holding down of the cap tightly on the bottle neck so as to prevent any possibility of the bulging of the cap during the crimping operation and the function of the piston 47 is to engage the crimping die to actuate it whereby the cap 15 will be fixedly secured to the neck of the bottle. The operation of crimping through the medium of the piston 47 is subsequent to the holding down of the cap upon the bottle neck. The piston 48 carries on its lower end a cap holding member which consists of a shank 61 extending in the lower end of the piston 48, a recess 62 being provided for such purpose, and secured to said lower end of the piston 48 by a transversely extending pin 63. The lower end of the member 61 is formed with a head 63^a which engages the cap when the piston 48 is forced downwardly due to the application of motive fluid. The member 61 not only performs the function just referred to but further constitutes a means for coupling certain elements of the crimping die with the piston 48 which will be presently referred to.
- 20 The crimping die comprises a pressure exerting member 64, a carrier 65 and an annularly arranged series of crimping elements 66, each of which is formed with a circular off-set 67 fulcrumed in an annular socket 68 formed in the lower face of the carrier 65. Each of the crimping elements 66 is independent of the other and capable of swinging inwardly and outwardly and provided with a flat edge 68 adapted to be engaged by the rounded edge 69 of the member 64 when the piston 47 is moved downwardly, whereby the crimping elements 66 are actuated to crimp a cap around the bottle neck. Each of the elements 66 is formed with a crimping edge 70. To limit the swinging inwardly of the elements 66 when in an inoperative position, the carrier 65 is provided with an extension 71. The carrier 65 is secured in position between the head 63^a of the member 61 and the lower end of the piston 48 and for such purpose the carrier 65 is formed with a centrally disposed opening through which extends the member 61, the head 63^a abutting against the lower face of the extension 71 of the carrier 65. The pressure exerting member 64 is formed integral with the lower end of the piston 47 and incloses the carrier 65. The form of crimping die illustrated is that as disclosed in my co-pending application Serial No. 520,086, filed Sept. 29, 1909.
- 25 The machine further embodies a fluid pressure operated trip mechanism for releasing the lever 42 so that the spring 44 will be released whereby the valve 38 will be automatically shifted to deflect the passage 30 of the incoming motive fluid. The fluid pressure operated trip mechanism comprises a cylinder 72 having a depending screw-threaded nipple 73 which is secured in the recess 25, the nipple 73 being hollow and opening into the port 24^a, the portion 26 of the wall of the port 24^a limiting the inward movement of the nipple 73. The cylinder 72 is closed by a cap 74. Abutting against the bottom of the casing 72 is a valve 75 provided with a stem 76 which projects through the cap 74 and the said projecting end is bifurcated as at 77. Interposed between the cap 74 and the upper face of the valve 75 and surrounding the stem 76 is a coil compression spring 78, the function of which is to normally maintain the valve 75 against the bottom of the casing 72 so as to close the port 79 through the nipple 73. The bifurcated end 77 of the stem 76 has mounted therein the right-angular extension 80 of a trigger 81, the latter being pivoted as at 82 to an arm 83 projecting laterally from the cylinder 72. The trigger 81 is formed with an upwardly extending arm 84 which when the trigger is in normal position, as shown in Fig. 1, is arranged in the path of the nose 43 of the lever 42, whereby said nose will engage said arm 84 and maintain the lever 42 in the position shown in Fig. 1 until the arm 84 is shifted from the path of the nose 43 so that the action of the spring 44 can shift the valve stem 41 and turn the valve 38 within the casing 29 so as to change the direction of the course of the incoming motive 35 fluid.

fluid. When the lever 42 is in position as shown in Fig. 1, the port 40 of the valve 38 establishes communication between the motive fluid supply pipe 32 and the passage 37 and the passage 39 of the valve 38 establishes communication between the conducting pipe 33 and the outlet 31. If the arm 84 is shifted from the path of the nose 43 of the lever 42, the spring 44 then comes into play and shifts the valve 38 so that the passage 40 will establish communication between the motive fluid supply pipe 32 and the conducting pipe 33 and the passage 39 of the valve 38 will establish communication between the outlet 31 and the passage 37.

The operation of the machine is as follows: It will be assumed that the parts are in the position as shown in Fig. 1. The motive fluid being supplied through the passages 40 and 37 and port 24 into the upper end of the cylinder 6, the motive fluid impacting against the surface 57 moves the piston 48 downwardly (prior to the movement of the piston 48 the cap is positioned in the throat formed by the annular arrangement of the crimping elements), which carries the crimping die and cap therewith until the cap engages over the mouth of the bottle, the motive fluid exerting pressure upon the piston 48 so that the head 63^a will hold the cap down securely on the neck of the bottle. The piston 48 when the face 58 of the portion 55 engages the shoulder 53 moves the piston 47 therewith, the cap being held securely upon the bottle neck, the piston 47 continues its movement, carrying the pressure exerting member 64 therewith, the latter engaging the crimping elements 66, actuating said elements, which 40 crimp the cap around the bottle neck. The pistons 47, 48 temporarily remaining in the piston stated until the pressure in the upper end of the cylinder overcomes the spring 78 whereby the valve 75 will be shifted upwardly carrying the valve stem 76 therewith, causing thereby the rocking of the trigger 81 on its pivot 82 so as to shift the arm 84 from below the nose 43. The releasing of the nose 43 allows of the spring 44 to come into action, the latter shifting the valve 38 so that the passage 39 will establish communication between the motive fluid supply pipe and the conducting pipe 33 and the passage 40 will establish communication between the passage 37 and the outlet 31. When the valve 38 has been shifted to the position just stated, the motive fluid will be conducted by the pipe 33 into the lower end of the cylinder and impact against the surfaces 59 and 60, elevating the piston 47 to relieve the pressure upon the crimping elements, piston 47 then elevates piston 48 removing the crimping die from the cap. The motive fluid in the upper portion of the cylinder 6 exhausts through the outlet 31. Af-

ter another bottle has been positioned upon the base 3 and a cap inserted in the throat, the operator moves the handle 43^a to the position shown in Fig. 1, whereby the valve 38 is shifted so that the passage 40 establishes communication between the motive fluid supply pipe 32 and the passage 37 and the passage 39 of the valve establishes communication between the conducting pipe 33 and the exhaust port 31, the incoming motive fluid forces the pistons 47, 48 downwardly and causes an exhaust from the lower end of the cylinder 6 through the conducting pipe 33 and outlet 31. The foregoing operation is continued until the desired number of bottles have been capped.

What I claim is:—

1. In a fluid pressure operated bottle capping machine, a pair of fluid pressure operated reciprocating pistons, a crimping die carried by one of said pistons and adapted to be operated by the other of said pistons for crimping a cap on a bottle neck, one of said pistons arranged within the other and with the outer independent of the inner and a fluid pressure operated trip mechanism adapted when operated to cause a deflection of the course of the incoming motive fluid to return the pistons to inoperative position and with the inner piston shifted by the outer piston.

2. A bottle capping machine comprising a cylinder, a pair of pistons arranged therein and extending therefrom and provided with motive fluid impact surfaces, and further arranged one within the other, one of said pistons operating in advance of the other when the pistons are shifted in one direction, valvular means whereby motive fluid is supplied to one end of the cylinder for shifting the pistons in one direction, one of said pistons carrying a cap holding means and the other of said pistons carrying a cap crimping die operating means, a cap crimping die arranged in operative relation with respect to said pistons, and a fluid pressure operated trip mechanism adapted when operated to shift said valvular means whereby the motive fluid will be supplied to the other end of the cylinder for shifting said pistons in the opposite direction.

3. In a fluid pressure operated bottle capping machine, a pair of fluid pressure operated reciprocating pistons, a cap crimping die carried by one of said pistons and adapted to be operated by the other of said pistons for crimping a cap on a bottle neck, and a fluid pressure operated means for changing the direction of flow of motive fluid for returning the pistons to inoperative position.

4. In a fluid pressure operated bottle capping machine, a pair of fluid pressure operated reciprocating pistons, a cap crimping

die carried by one of said pistons and adapted to be operated by the other of said pistons for crimping a cap on a bottle neck, a fluid pressure, operated means for changing the direction of flow of motive fluid for returning the pistons to inoperative position, and means for regulating the application of pressure to said piston.

5. In a fluid pressure operated bottle capping machine, a pair of fluid pressure operated reciprocatory pistons, a cap crimping die carried by one of said pistons and adapted to be operated by the other of said pistons for crimping a cap on a bottle neck, a fluid pressure operated means for changing the direction of flow of the motive fluid for returning the pistons to inoperative position, means for providing a fluid cushion for the pistons when moving in one direction, 15 and means for providing a fluid cushion when the pistons are moving in the opposite direction.

6. In a fluid pressure operated bottle capping machine, a pair of fluid pressure operated reciprocatory pistons, a cap crimping die carried by one of said pistons and adapted to be operated by the other of said pistons for crimping a cap on a bottle neck, a fluid pressure operated means for changing the direction of flow of the motive fluid for returning the pistons to inoperative position, means for providing a fluid cushion for the pistons when moving in one direction, means for providing a fluid cushion when the pistons are moving in the opposite direction, and means for regulating the application of pressure to said pistons.

7. A fluid pressure operated bottle capping machine comprising a cylinder, a reciprocatory cap crimping die carrying element, operating within and projecting beyond said cylinder, means whereby motive fluid is supplied to said cylinder for operating said elements in one direction, and means actuated on the rise of pressure within the cylinder for automatically changing the course of the fluid supplied to the cylinder for directing the fluid against one of said elements for operating them in the opposite direction.

8. A fluid pressure operated bottle capping machine comprising a cylinder, a reciprocatory cap crimping die carrying element, a reciprocatory cap crimping die operating element, said elements operating within and projecting from said cylinder, means whereby motive fluid is supplied to said cylinder for operating said elements in one direction, means actuated on the rise of pressure within the cylinder for automatically changing the course of the fluid supplied to the cylinder for directing the fluid against one of said elements for operating them in the opposite direction, and means whereby the elements are operated in

unison when the course of the fluid is changed.

9. A fluid pressure operated bottle capping machine comprising a cylinder, a reciprocatory cap crimping die carrying element, a reciprocatory cap crimping die operating element, said elements operating within and projecting from said cylinder, means whereby motive fluid is supplied to said cylinder for operating said elements in one direction, means actuated on the rise of pressure within the cylinder for automatically changing the course of the fluid supplied to the cylinder for directing the fluid against one of said elements for operating them in the opposite direction, and means within the cylinder for providing a fluid cushion when the elements are operating in the opposite direction.

10. A fluid pressure operated bottle capping machine comprising a cylinder, a reciprocatory cap crimping die carrying element, a reciprocatory cap crimping die operating element, said elements operating within and projecting from said cylinder, means whereby motive fluid is supplied to said cylinder for operating said elements in one direction, means actuated on the rise of pressure within the cylinder for automatically changing the course of the fluid supplied to the cylinder for operating them in the opposite direction, means whereby the elements are operated in unison when the course of the fluid is changed, means within the cylinder for providing a fluid cushion for the elements when operating in one direction, and means within the cylinder for providing a fluid cushion when the elements are operating in the opposite direction.

11. A fluid pressure operated bottle capping machine comprising a cylinder, a reciprocatory cap crimping die carrying element, a reciprocatory cap crimping die operating element, one of said elements arranged within the other, means for supplying fluid pressure to each end of the cylinder, each of said elements provided with means whereby on a supply of motive fluid to one end of the cylinder, said inner element is moved outwardly in unison with the outer element until the inner element is arrested by the bottle neck to position the cap, means whereby said outer element after the arresting of the inner element is moved independently of the inner element to crimp the cap, and means whereby on a supply of fluid to the other end of the cylinder, said outer element will be shifted inwardly in advance of and then in unison with the inner element to clear the cap to allow the removal of the bottle.

12. A fluid pressure operated bottle capping machine comprising a cylinder, a reciprocatory cap crimping die carrying

- element, a reciprocatory cap crimping die operating element, one of said elements arranged within the other, means for supplying fluid pressure to each end of the cylinder, each of said elements provided with means whereby on a supply of motive fluid to one end of the cylinder said inner element is moved outwardly in unison with the outer element until the inner element is arrested by the bottle neck to position the cap, means whereby said outer element after the arresting of the inner element is moved independently of the inner element to crimp the cap, means whereby on a supply of fluid to the other end of the cylinder, said outer element will be shifted inwardly in advance of and then in unison with the inner element to clear the cap to allow the removal of the bottle, means within the cylinder to provide a fluid cushion for the movement of said elements in one direction, and means within the cylinder for providing a fluid cushion for the movement of the elements in the opposite direction.
13. A fluid pressure operated bottle capping machine comprising a cylinder, a piston 48 arranged therein and projecting therefrom and having its inner portion formed of two different diameters, a piston 47 surrounding said piston 48 and having a cup-shaped inner end inclosing the inner portion of said piston 48 and of a diameter to snugly engage the inner face of the cylinder, said cup-shaped portion of the piston 47 provided with a shoulder adapted to be engaged by the enlarged inner portion of the piston 48, a cap crimping die carried by the piston 48, a cap crimping die operating means carried by the piston 47 and adapted to engage the die carried by the piston 48 for crimping the cap around the bottle neck, and means for supplying fluid pressure to said cylinder for reciprocating said pistons.
14. A fluid pressure operated bottle capping machine comprising a cylinder, a piston 48 arranged therein and projecting therefrom and having its inner portion formed of two different diameters, a piston 47 surrounding said piston 48 and having a cup-shaped inner end inclosing the inner portion of said piston 48 and of a diameter to snugly engage the inner face of the cylinder, said cup-shaped portion of the piston 47 provided with a shoulder adapted to be engaged by the enlarged inner portion of the piston 48, a cap crimping die carried by the piston 48, a cap crimping die operating means carried by the piston 47 and adapted to engage the die carried by the piston 48 for crimping the cap around the bottle neck, means for supplying fluid pressure to said cylinder for operating the pistons in one direction, means actuated on the rise of pressure within the cylinder for automatically changing the course of the fluid supplied to the cylinder to operate the pistons in the opposite direction, and means whereby the pistons are operated in unison when the course of the fluid is changed.
15. A fluid pressure operated bottle capping machine comprising a cylinder, a piston 48 arranged therein and projecting therefrom and having its inner portion formed of two different diameters, a piston 47 surrounding said piston 48 and having a cup-shaped inner end inclosing the inner portion of said piston 48 of a diameter to snugly engage the inner face of the cylinder, said cup-shaped portion of the piston 47 provided with a shoulder adapted to be engaged by the enlarged inner portion of the piston 48, a cap crimping die carried by the piston 48, a cap crimping die operating means carried by the piston 47 and adapted to engage the die carried by the piston 48 for crimping the cap around the bottle neck, means for supplying fluid pressure to said cylinder for operating the pistons in one direction, means actuated on the rise of pressure within the cylinder for automatically changing the course of the fluid supplied to the cylinder to operate the pistons in the opposite direction, means whereby the pistons are operated in unison when the course of the fluid is changed, means within the cylinder for providing a fluid cushion when the pistons are moving in one direction, and means within the cylinder for providing a fluid cushion when the pistons are moving in the opposite direction.
16. A fluid pressure operated bottle capping machine comprising a cylinder, a piston 48 arranged therein and projecting therefrom and having its inner portion formed of two different diameters, a piston 47 surrounding said piston 48 and having a cup-shaped inner end inclosing the inner portion of said piston 48 of a diameter to snugly engage the inner face of the cylinder, said cup-shaped portion of the piston 47 provided with a shoulder adapted to be engaged by the enlarged inner portion of the piston 48, a cap crimping die carried by the piston 48, a cap crimping die operating means carried by the piston 47 and adapted to engage the die carried by the piston 48 for crimping the cap around the bottle neck, means for supplying fluid pressure to said cylinder for reciprocating said pistons, and means mounted upon the cylinder whereby when the pistons are moving in one direction, the fluid will be exhausted from one end of the cylinder and when moving in the opposite direction, the fluid will be exhausted from the other end of the cylinder.
17. A fluid pressure operated bottle capping machine comprising a cylinder, a reciprocatory cap crimping die carrying element, a reciprocatory cap crimping die op-

- erating element, one of said elements arranged within the other, means for supplying fluid pressure to each end of the cylinder, each of said elements provided with means whereby on a supply of motive fluid to one end of the cylinder, said inner element is moved outwardly in unison with the outer element until the inner element is arrested by the bottle neck to position the cap, means whereby said outer element after the arresting of the inner element is moved independently of the inner element to crimp the cap, means whereby on a supply of fluid to the other end of the cylinder, said outer element will be shifted inwardly in advance of and then in unison with the inner element to clear the cap to allow the removal of the bottle, and means for regulating the application of pressure to said piston.
18. In a fluid pressure operated bottle capping machine, a cylinder, a pair of fluid pressure reciprocatory pistons operating therein and projecting therefrom, a cap crimping die carried by one of said pistons and adapted to be operated by the other of said pistons for crimping a cap on a bottle neck, a valve mechanism mounted upon said cylinder for alternately establishing communication between each end of the cylinder and a motive fluid supply whereby motive fluid is alternately supplied to each end of the cylinder for reciprocating the pistons, and means mounted upon and communicating with the cylinder and actuated on the rise of pressure within the cylinder at one end thereof to shift the said valve mechanism whereby the direction of flow of the fluid supplied to the cylinder will be changed.
19. In a fluid pressure operated bottle capping machine, a cylinder, a pair of fluid pressure reciprocatory pistons operating therein and projecting therefrom, a cap crimping die carried by one of said pistons and adapted to be operated by the other of said pistons for crimping a cap on a bottle neck, a valve mechanism mounted upon said cylinder for alternately establishing communication between each end of the cylinder and a motive fluid supply whereby motive fluid is alternately supplied to each end of the cylinder for reciprocating the pistons, and means mounted upon and communicating with the cylinder and actuated on the rise of pressure within the cylinder at one end thereof to shift the said valve mechanism whereby the direction of flow of the fluid supplied to the cylinder will be changed, means for regulating the application of pressure to said piston, means within the cylinder at one end thereof to provide a fluid cushion for the movement of the pistons in one direction, and means within the cylinder at the other end thereof for providing a fluid cushion for the pistons when moving in the opposite direction.
20. In a fluid pressure operated bottle capping machine, a cylinder, a pair of fluid pressure reciprocatory pistons operating therein and projecting therefrom, a cap crimping die carried by one of said pistons and adapted to be operated by the other of said pistons for crimping a cap on a bottle neck, a valve mechanism mounted upon said cylinder for alternately establishing communication between each end of the cylinder and a motive fluid supply whereby motive fluid is alternately supplied to each end of the cylinder for reciprocating the pistons, means mounted upon and communicating with the cylinder and actuated on the rise of pressure within the cylinder at one end thereof to shift the said valve mechanism whereby the direction of flow of the fluid supplied to the cylinder will be changed, means for regulating the application of pressure to said piston, means within the cylinder at one end thereof to provide a fluid cushion for the movement of the pistons in one direction, and means within the cylinder at the other end thereof for providing a fluid cushion for the pistons when moving in the opposite direction.

In testimony whereof I affix my signature in presence of two witnesses.

ROSS V. CAGGS.
